UNITED STATES PATENT OFFICE.

JOHN J. HOWE AND TRUMAN PIPER, OF DERBY, CONNECTICUT, ASSIGNORS TO HOWE MANUFACTURING COMPANY, OF DERBY, CONNECTICUT.

JAPANNING PINS.

Specification of Letters Patent No. 15,111, dated June 10, 1856.

To all whom it may concern:

Be it known that we, JOHN J. HOWE and TRUMAN PIPER, of Derby, in the State of Connecticut, have invented a new and useful Improvement in the Process of Japanning Pins, of which the following is a full, clear, and exact description, reference being had to the accompanying drawings, making part of this specification, in which—

- 10 Figure 1, represents a vertical section of a vat with pins hanging with their heads downward in the Japan varnish, or compound contained in the vat. Fig. 2, represents a like view of the same vat with the 15 pins hanging by their heads with the points downward in the Japan varnish or compound; and Fig. 3 is a face view of a pierced plate of metal in which the pins are inserted.

The same letters indicate like parts in all 20 the figures.

In our improved process the pins to be japanned are stuck into a sheet of paper and at right angles or nearly so to the surface thereof, and to such a depth that the heads 25 will project to some distance from the surface of the sheet of paper. And in that condition the pins are dipped head foremost to the required depth in the Japan varnish or compound, and when sufficiently coated they 30 are removed to a suitable oven to bake the japan, and when the japan is properly dried and baked the pins are then hung by their heads and dipped points downward to the required depth in the Japan varnish or compound. 35 And when so dipped they are again put in a suitable oven to dry and bake the japan in the usual mode of performing the well-known process of japanning.

We will now describe the mode of applying our invention which we have practiced with success.

The Japan varnish or compound is to be 45 prepared in the usual and well known way, and put into a vat *a* to a suitable depth. Above this vat there is an open frame *b* provided with four vertical guide rods *c*, one only shown in the drawings, which extend down therefrom and which are adapted to slide in suitable loops or ways attached to the outside of the vat to guide the frame in its movements up and down given by a screw

e fitted to turn in an arm projecting from the frame *b* and tapped into a nut in a projection *f* from the side of the vat. 55

By means of a machine invented by us and for which we contemplate making application for Letters Patent of even date with this application, we stick a large number of 60 pins *g* through holes in a thin plate of metal *h* and into a sheet of paper *i* held against the back of the said metal plate. The holes in the metal plate are large enough to receive the shank or barrel of the pins freely but 65 not to permit the heads to pass through; we stick the pins into the sheet of paper to about one third their length from the point. We then take the plate with the sheet of paper thus charged with pins, and lay the metal 70 plate on top of the frame *b* with the sheet of paper above the plate and with the heads of the pins hanging downward, the shanks being held by the grip of the paper; and then, by turning the screw, let down the 75 frame until that part of the pins depending below the plate, is immersed in the Japan varnish or compound, and when thoroughly coated we draw up the frame and carry the plate with the pins to, and put it in an oven 80 such as is usually employed for baking japan, and there leave it the required length of time well known to those acquainted with the process of japanning. And so we proceed until the required number have been 85 dipped and baked.

When the pins, treated as above described, are taken from the oven, we turn the metal plate upside down and draw off the sheet of paper so that all the pins will hang in the 90 plate by their heads. The plate is then again placed on the frame *b* but with the points downward and dip the pins in the Japan varnish or compound points downward, and to such depth that all that portion of the surface of the pins which was not dipped in the previous operation shall become coated, and then we again put them in the oven to be baked as before to complete the process. In 95 this way we are enabled to thoroughly coat the entire surface of the pins and to bake the japan without injury to the surface, and avoid all those imperfections on the surface which are unavoidable when japanned by any other process. 100

It will be obvious from the foregoing that 105

the pins may be dipped and baked first one end and then the other by simply sticking them in a sheet of paper, or equivalent substance, and after the first, and before the 5 second dipping and baking, sticking them a little farther into the paper that in succession the entire surface may be dipped and baked. But the process will be more rapidly and efficiently worked with the perforated 10 plate of metal or other equivalent substance.

What we claim as our invention in the process of japaning pins, is—

1. Dipping a portion of the length of the pins in the compound while inserted in a 15 sheet of paper and with one end downward and then subjecting them to the baking operation, substantially as described, in combination with the second dipping and baking in the reversed direction to japan the remain-

ing portion, substantially as and for the 20 purpose specified.

2. And we also claim controlling the pin during the process, substantially as described, by sticking the pins into the sheet of paper through holes in a plate of metal or 25 equivalent substance the said holes being of sufficient size for the free passage of the shanks or barrels of the pins, but not for the heads so that after the first dipping and baking, by reversing the plate and pulling off 30 the sheet of paper the pins will hang by their heads for the second dipping and baking, as set forth.

JNO. J. HOWE.
TRUMAN PIPER.
